UNITED STATES PATENT OFFICE

2,443,021

MOVABLE ANODE STRUCTURE

Igor B. Bensen, Schenectady, N. Y., assignor to
General Electric Company, a corporation of
New York

Application November 10, 1945, Serial No. 627,954

3 Claims. (Cl. 250—162)

1

My invention relates to cathode ray tubes and, particularly, to devices for controlling the dimensions of the cathode ray beam in such tubes.

In cathode ray tubes which are used for electron optical purposes, such as electron microscopes and electron diffraction instruments, it is desirable to have a narrow beam of electrons for radiating an object being examined. On the other hand, a very narrow beam of electrons is difficult to detect and to focus on a chosen spot of a specimen and is particularly difficult to center on the fluorescent screen or end wall of the tube. Accordingly, it is a primary object of my invention to provide a new and improved anode structure for a cathode ray tube which provides selectively a broad and a narrow beam of electrons.

It is another object of my invention to provide a new and improved anode for a cathode ray tube having a positionable aperture for controlling the dimensions of a cathode ray beam.

It is still another object of my invention to provide a new and improved anode for a cathode ray tube having a fixed portion and a movable portion and externally accessible means for controlling the position of the movable portion.

An important feature of my invention is the use, in a cathode ray tube used for electron optical purposes, of an anode having a movable portion which includes two apertures of different dimensions and means to vary the position of the movable portion to employ a larger aperture to center the electronic beam of the tube on a fluorescent screen and on a selected spot of a specimen to be examined. Externally accessible means are provided for moving the larger aperture and replacing it with a smaller aperture to define a very narrow beam of electrons for illuminating or radiating a desired spot of the object under examination.

The aspects of the invention which I desire to protect herein are pointed out with particularity in the appended claims. The invention itself, together with further objects and advantages thereof, may best be understood by reference to the following description taken in connection with the accompanying drawing in which Fig. 1 is a sectional view of an electron diffraction instrument suitably embodying the invention; Figs. 2 and 3 are front and rear views, respectively, of an anode structure employed in the instrument of Fig. 1; and Fig. 4 is a sectional view taken along the line 4—4 of Fig. 2.

Referring particularly to Fig. 1, there is shown an electron diffraction instrument comprising an elongated vacuum-tight container which consists mainly of a metal part 1. At one end, the container is closed by a glass window 2 having a fluorescent material 3 on its inner surface and, at the other end of the container, there is pro-

2

vided a glass insulator 4 which serves to support an electron source in the form of a filamentary cathode 5.

The cathode is surrounded by an apertured metal member 6 which confines emitted electrons to a beam and which is cooperatively positioned with respect to an apertured anode structure 7 supported in contact with the main envelope part 1. In the normal use of the apparatus, the envelope 1 and the anode 7 are maintained at ground potential, while the cathode is held at a large voltage below ground potential, such as by connection to a potential source 8 so that the electrons emitted from the cathode are projected through the apertured anode 7 toward the fluorescent screen 3.

In using the apparatus as an electron diffraction instrument, it is desired to cause the electron stream proceeding from the cathode 5 to produce a narrow beam which normally is centered at the center of the fluorescent screen 3, but which may be caused to scatter, as by reflection from a specimen 9 supported by any suitable manipulating device 10 to cause a deflection pattern characteristic of the crystalline structure of the material 9 to appear on the fluorescent screen 3. Alternatively, if the specimen 9 is a very thin layer of a crystalline material, the electron beam may be caused to pass through the specimen to form a re-grouping of the electrons in accordance with a deflection pattern which is characteristic of the crystal. Of course, prior to formation of the electron beam, the region within the container 1 must be suitably evacuated, as for example by any vacuum pump (not shown) attached to a tubulation 11.

Referring to Figs. 2-4 jointly, I have there shown an enlarged view of the anode structure 7 of Fig. 1. This structure comprises a circular metallic disk 12 having on one side a centrally disposed circular recess or shoulder 13 and on its opposite side a longitudinally extending tubular portion 14. At the center of the recess 13 there is provided an opening 15 which tapers to the opposite side of the disk 12, and seated in the recess 13 is a circular disk 16 having a diameter smaller than the diameter of the recess 13. The movable disk 16 is provided near its center with two tiny apertures 17, 18, the purpose of which is pointed out later in this description and which are spaced approximately equal distances from the center of the disk 16. Moreover, the aperture 17 is considerably larger than the aperture 18, having a diameter approximately four times that of the aperture 18.

The disk 16 is maintained within the recess 13 and is pressed against the disk 12 by a retaining arm 19 secured to the outer surface of the disk 12, and is resiliently biased toward the left-hand side of the anode, as seen in Fig. 2, by a

spring 20 formed of any suitable spring material such as beryllium copper. The spring 20 engages at one end a hole 21 in the edge of the disk 16 and at its other end is secured in the hole 22 in the disk 12 by means of a grooved retaining washer 23 and a screw 24.

In order that the disk 16 may be moved to any desired spot in the recess 13 selectively to bring either the aperture 17 or the aperture 18 in the path of the electron beam, I provide means for moving the disk 16 in two rectilinearly disposed directions. This means comprises a pair of movable rods 25, 26 which engage the outer edge of the disk 16 at rectilinearly disposed positions. Each of the rods at its other end carries a roller 27 which engages an inclined plane surface 28 on a movable piston 29. The piston 29 is maintained within a cylinder 30 and is resiliently biased toward the right by means of a spring 31 which is compressed between the left-hand end of the piston 29 and the surface of a retaining cap 32. The cap 32 slides over one end of the cylinder 30 and is attached thereto by means of a pin 33. The pin 33 likewise passes through a longitudinal slot 34 in the piston 29, the length of the slot 34 being equal to the amount of movement required to move the disk 16 between desired limits. At its other end, the piston 29 is provided with an adjustable screw 35 which, in turn, engages a suitable operating mechanism, one form of which is illustrated in Fig. 1 as a rack 36 operated by a pinion 37. The pinion 37 preferably is operated by an externally accessible control knob and is provided with a suitable bearing arrangement, such as a Sylphon bellows (not shown) to maintain the vacuum-tight connection between the internal and external operating mechanisms.

The actuating rods 25, 26 preferably lie respectively in radially extending slots 38, 39 in the disk 12 and are retained in these slots by a plate 40 which is affixed to the disk 12 by a plurality of screws 41. As previously explained, the entire anode structure fits within the metallic container 1 and may be provided with an orienting tab 42 to assist in locating the structure in the desired longitudinal and angular positions.

In the operation of electron diffraction instruments of Fig. 1, it is desired, prior to obtaining a diffraction pattern, to center the cathode ray beam on the fluorescent screen 3. To this end, the cathode ray beam emitted by the filamentary cathode 5 is allowed to pass through the larger aperture 17 and to be focussed by means of a focussing yoke (not shown) to fall upon the center of the fluorescent screen 3. Thereafter, an object to be examined is placed in the path of this beam by means of manipulator 10 so that the beam either passes through the object, in the case of a very thin object, or is reflected therefrom at a desired angle. For optimum definition of the diffraction lens of the pattern, it is desirable that a very narrow beam of electrons be used. Accordingly, after the object has been oriented by means of the manipulator 10 so that the beam falls upon a desired spot, the anode disk is moved in a substantially rectilinear motion by means of the two rods 25, 26 actuated by the piston 29 to move the aperture 17 from the center of the path of the electron beam and to replace it with the smaller aperture 18. Due to the effect of the spring 20, the motion imparted to the

disk 16 by the rods 25, 26 is slightly rectilinear. However, due to the extremely small distances involved which are of the order of 20 to 40 millimeters, substantial rectilinear motion is imparted to the disk 16.

An important advantage of my improved anode structure is that it clearly facilitates the centering of the beam in an electron diffraction instrument. Thus, by the use of a larger aperture 17, which may be of the order of 10 millimeters, it is relatively easy to obtain a spot upon the fluorescent screen 3 and to center that spot by means of a focussing yoke. Thereafter the disk 16 is moved by means of the rods 25, 26 until the large spot due to the aperture 17 passes off the screen and is replaced by a considerably smaller spot due to the aperture 18. All manipulations are effected by easily controlled knobs outside the diffraction instrument and, throughout its movement, the disk 16 is pressed against the anode-disk 12 so that no variations in voltage of the disk 16 are obtained to affect the focus of the electron beam.

While my invention has been described by reference to a particular embodiment thereof, it will be understood that numerous modifications may be made by those skilled in the art without actually departing from the invention. I therefore aim in the appended claims to cover all such modifications as fall within the true spirit and scope of the foregoing disclosure.

What I claim as new and desire to secure by Letters Patent of the United States is:

1. The combination, in a cathode ray tube, of an enclosing envelope, an anode supported within said envelope, said anode comprising a fixed portion, a movable portion, means maintaining an electrically conductive connection between said portions, and means whereby the position of said movable portion may be varied.

2. A cathode ray tube comprising an enclosing envelope, means for producing a cathode ray beam, an anode structure supported within said envelope, said structure including a fixed portion and a movable portion, means external to said envelope for selectively varying the position of said movable portion, and means maintaining conductive connection between said portions as said position is varied.

3. The combination, in an electron optical instrument, of an evacuated envelope, means within said envelope for producing a cathode ray beam, an anode supported within said envelope, said anode comprising a fixed portion and a movable portion, said movable portion having a pair of apertures therein, a viewing screen, and externally accessible means for moving said movable portion to direct said cathode beam through a selected one of said apertures to said screen.
